CLAIM

The ornamental design for an LED light fixture, as shown and described.

DESCRIPTION

FIG. 1 is a front perspective view of a first embodiment of an LED light fixture showing our new design;

FIG. 2 is a bottom view thereof;

FIG. 3 is a front perspective view of a reflector used in the first embodiment, shown separate for completeness of illustration;

FIG. 4 is a front perspective view of a heat sink module and an LED module used in the first embodiment, shown separate for completeness of illustration;

FIG. 5 is an enlarged bottom view of the LED module of the first embodiment, shown separate for completeness of illustration;

FIG. 6 is a side view thereof, the opposite side being identical;

FIG. 7 is a bottom view of a second embodiment of an LED light fixture;

FIG. 8 is a front perspective view of a reflector used in the second embodiment, shown separate for completeness of illustration;

FIG. 9 is a front perspective view of a heat sink module and an LED module used in the second embodiment, shown separate for completeness of illustration;

FIG. 10 is an enlarged bottom view of the LED module of the second embodiment, shown separate for completeness of illustration; and,

FIG. 11 is a side view thereof, the opposite side being identical.

The broken lines are environmental only and form no part of the claimed design.
